UNITED STATES PATENT OFFICE.

HARRY L. CROSON, OF OAKLAND, CALIFORNIA, ASSIGNOR OF ONE-HALF TO WILLIAM W. LAIDLEY, OF PIEDMONT, CALIFORNIA.

COLLAR FASTENER.

Application filed June 18, 1923. Serial No. 646,120.

To all whom it may concern:

Be it known that I, HARRY L. CROSON, a citizen of the United States, residing at Oakland, in the county of Alameda and State of California, have invented certain new and useful Improvements in Collar Fasteners, of which the following is a specification.

My invention relates to collar-fastening means, and especially to a fastener for attaching the collar to the shirt band at the back.

The common collar button for men's collars so universally sold and used, and with which I am familiar, consists of a round base in the form of a disk, having a central stem projecting therefrom that terminates in a small ball. This ball, spaced from the disk, serves as a guide in engaging the buttonhole of the collar, and fastens the collar 20 to the shirt when the ball passes through the hole. While the button is convenient and effective, yet it has deficiencies I have found, and some of which are: that the ball projects out so far that it is annoying, especially 25 if one's coat collar is well fitting or tight, which causes the back of the button to press against the neck, and also creates a small hump at the coat-collar region; also, the ball of the present collar button is a 30 hindrance in tying the common neckties in use, as the tie very frequently wedges under the ball, which retards the effective sliding of it around the collar. Another disadvantage of the round button is, that when 35 dropped to the floor, it may roll to a near or remote spot, necessitating at times quite an extensive search for the same and consuming much time, especially in poor light.

The primary object of my invention is the 40 provision of a flat fastener that overcomes the above objections by practically dispensing with a projection, thereby obviating pressure on the neck and coat protuberance, and permitting the tie to slide above the 45 fastener. Also, if my fastener is dropped to the floor, it falls direct and without rolling, as it is flat and preferably of lustrous metal, which enhances the immediate finding thereof even in dark situations.

50 My invention possesses additional merits, such as extreme cheapness in manufacture; ease of application through the hole of the neck-band and the positive retention therein; the quick slipping thereof through the

collar-button hole and the neat appearance 55 presented. It can be sold so cheaply that laundries could insert them, as a courtesy, in the neck-bands of shirts as a regular practice for their customers, thus saving them 60 lots of time.

Other objects and advantages of the invention, will appear in the subjoined description of the accompanying sheet of drawings, in which:

Figure 1 is a front view of my fastener 65 and Fig. 2 a side view of it.

Fig. 3 is a vertical cross-section through a collar, tie, and a portion of a shirt, the collar being attached to the shirt by my invention which is shown in full side view. 70 The transverse scale in this figure is greatly enlarged for the purpose of clarity.

Fig. 4 is a front view of a portion of a shirt showing my fastener in position in the 75 neck-band thereof.

Fig. 5 shows a modified form of fastener, the same being sewed on the neck-band of the shirt.

Fig. 6 shows my invention as part of a 80 stiff neckband on a shirt, the tongue being equivalent to the tongue of the other figures.

Fig. 7 is a side view of my fastener as when made perfectly flat.

Adverting to the drawing and figures 85 thereof: Fig. 1 represents my fastener substantially formed in the shape of the letter T, and the numeral 1 represents the head of the fastener and 2 the tongue thereof. The length of the tongue being approximately one-half the height of the fastener. 90

In Fig. 2, it will be observed that the thickness of the fastener, is small compared to the width of the tongue or the height of the head. I prefer to manufacture the article in the form of a stamping, from sheet-metal of any suitable material. At the union of the tongue and head, as at 3, I prefer to form an obtuse-angle bend, and near thereto a reverse obtuse-angle bend, so that the two bends together form a slight 100 ogee and offset the tongue in a plane parallel to the plane of the head as shown in this figure.

In Fig. 3, the height of the collar 4, neck-band 5 and necktie 6, are shown in true 105 relation, but their transverse views including the fastener, are purposely enlarged to show clearly the relative arrangement of

the associated parts thereat, and in particular, the usual construction of the union of neck-band 5 and shirt 7. The latter is inserted in the neck-band as at 8 and stitched therein, and at the top of the band, as at 9, an additional piece is stitched usually inclosing a stiffening strip 10.

The finished neck-band of a shirt, has an inverted pocket 11 at the back thereof, 10 Fig. 4, and is provided about mid-way of its height with a button-hole 12, for housing and supporting the usual collar button. In Figs. 3 and 4, my collar fastener is shown positioned in the said button-hole 12, the 15 tongue 2 depending therefrom, and the head 1 snugly held flat in the pocket, the height of the head being such to accommodate the distance between the hole and the top of the inverted pocket.

20 With reference to Figs. 1 and 2 it is pointed out that the head 1 has two virtually straight and parallel side edges, which are joined to round end edges, and that the tongue 2 extends approximately midway 25 from one side edge and also has two virtually straight and parallel side edges at approximately right angles to the side edges of the head, and that the side edges of the tongue are joined to a round edge at the 30 free end of the tongue. By means of such a construction the collar fastener is easily inserted into its place in the neckband and is held there very nicely, while at the same time by means thereof the attachment or detachment of a collar is facilitated and the 35 free sliding of a tie around the collar is allowed. These are important advantages over former collar fasteners in which projections, slots and notches are formed, thereby 40 catching the threads of the tie and preventing the tie from sliding freely around the collar.

The tie 6, Fig. 3, is shown free above the fastener, enabling it to slide freely within 45 the collar, the whole assemblage giving the

wearer a comfortable feeling at the back of the neck.

In some cases I may prefer to sew or secure in any approved manner, my fastener direct to the shirt or neck-band as at 13, 50 Fig. 5, thus obviating the need of removably inserting a collar fastener thereat. Again, I may wish to have the latter feature in view, and provide a shirt with my invention as part of the neck-band. This I accomplish 55 by providing a stiff and pliable tongue 2, as shown in Fig. 6.

Having thus illustrated and described my invention in its preferred form, I wish it understood that the same may be modified 60 as practice suggests. Therefore, the patent protection that I desire, is all of that which comes within the spirit and scope of the invention as claimed.

I claim:

A collar fastener comprising a stamping of sheet material provided with a head of a width adapted to fill the space between the button hole and the top of the pocket in the neckband of a shirt, the head having two virtually straight and parallel side edges joined to round end edges, and a tongue extending approximately midway from one side edge of the head and having two virtually straight and parallel side edges at approximately right angles to the side edges of the head, the side edges of the tongue being joined to a round edge at the free end of the tongue, and the tongue having a obtuse-angled bend at its junction with the head, and a reverse, obtuse-angled bend near to the first bend, so that the free end of the tongue is in a plane virtually parallel with the plane of the head, the edges and surfaces of the finished collar fastener being 80 free from projections, depressions or notches.

In testimony whereof I affix my signature.

HARRY L. CROSON.
